UNITED STATES PATENT OFFICE.

JOHN FRANCES KILLION, OF NORFOLK, MASSACHUSETTS, ASSIGNOR TO WHITING CHAIN COMPANY, A CORPORATION OF MASSACHUSETTS.

DESIGN FOR A MESH BAG.

Application filed August 29, 1922. Serial No. 3,591. Term of patent 7 years.

To all whom it may concern:

Be it known that I, JOHN FRANCES KILLION, a citizen of the United States, residing at 15½ Park Ave., Norfolk County, Attleboro, Mass., have invented a new, original, and ornamental Design for Mesh Bags, of which the following is a specification, reference being had to the accompanying drawing, forming part thereof.

The figure is a side view of a mesh bag, showing my new design.

I claim:

The ornamental design for a mesh bag as shown.

JOHN FRANCES KILLION.
